UNITED STATES PATENT OFFICE.

JAMES J. WOOD, OF FORT WAYNE, INDIANA, ASSIGNOR TO GENERAL ELECTRIC COMPANY, A CORPORATION OF NEW YORK.

ROTARY REFRIGERATING-MACHINE.

1,164,245.

Specification of Letters Patent. Patented Dec. 14, 1915.

Application filed April 22, 1914. Serial No. 833,300.

To all whom it may concern:

Be it known that I, JAMES J. WOOD, a citizen of the United States, residing at Fort Wayne, in the county of Allen, State of Indiana, have invented certain new and useful Improvements in Rotary Refrigerating-Machines, of which the following is a specification.

My present invention relates to rotary refrigerating machines of the type comprising a closed condenser, within which is arranged a compressor member and a closed refrigerator, the condenser and refrigerator being connected by a hollow shaft. The condenser in such a refrigerating machine contains a liquid, such as sulfur-dioxide, which is liquefied by compression and which subsequently vaporizes in the refrigerator, producing a fall of temperature. The members of the machine also contain a lubricant for the working parts thereof which becomes mixed with the refrigerating liquid to a considerable extent in the operation of the machine, for reasons which will be explained later.

My invention comprises certain improvements in such refrigerating machines by which their efficiency is increased and by which the disassembly of the parts thereof is facilitated.

In the operation of the refrigerating machines of the type described above as heretofore constructed, I have discovered that at the relatively low speeds at which such machines must operate for the proper operation of the compressors, the lubricant and the refrigerating liquid are liable to mix and form an emulsion, and that if this occurs the efficiency of the machine is materially reduced; whereas, if the oil and refrigerating liquid are kept from mixing so that the refrigerating liquid remains in contact with the drums and the oil forms a film inside of the refrigerating liquid, the machine will operate at maximum efficiency. At ordinary speeds of operation there is also a tendency for the oil and refrigerating liquid to collect to some extent at the lowest points of the condenser drum and the refrigerator drum, instead of distributing themselves uniformly about the inner surfaces of the drums by centrifugal force. The emulsion of oil and refrigerating liquid is not a good conductor of heat and does not

cool the drums as rapidly as would be the case if the refrigerating liquid were free from oil. If the oil and refrigerating liquid collect at the bottom of the drums in sufficient quantity, the whole machine will be caused to rotate as a unit and will thus become inoperative.

My invention has for one of its objects to provide means which will effectually prevent the mixing of the lubricant and refrigerating liquid into an emulsion in the operation of the machine. This mixing may occur in the ordinary type of machine heretofore employed in the condenser drum or in the refrigerating drum, or both, and I have found that by providing one or both of these chambers with blades extending radially inward from the drum at the point of greatest diameter, the oil and the liquid, as they flow from the compressor member into the condenser drum, will be carried around together. The refrigerating liquid, being heavier, will be distributed about the inner surface of the drum, and the oil, which is lighter in weight, will float as a film on the inner surface of the refrigerating liquid. The gathering member or scraper will take up the oil and the refrigerating liquid in the ordinary manner and deliver it into the reservoir, but since the oil and liquid exist as separate and distinct films, they will be delivered into the reservoir in this same form, and most of the oil will rise to the surface of the body of refrigerating liquid contained therein. Some oil will, however, become mixed with the refrigerating liquid and so will be carried over to the refrigerating drum. In order to prevent this oil from forming an emulsion with the refrigerating liquid after it has reached the refrigerating drum, I provide this drum also with a series of inwardly projecting blades at the point of greatest diameter, the blades in this case being considerably larger than in the condenser drum, since they have to handle a larger volume.

By another feature of my invention, I am able to very considerably facilitate the disassembly of the machine. In refrigerating machines of the type described above as heretofore constructed, a tube, which is fastened to the compressor member and extends into the refrigerator through the hollow shaft, for conveying the refrigerating liquid

to the refrigerator, has had rigidly connected thereto an oil separator, in order to hold the oil separator against rotation with reference to the tube and compressor member 5 and in its proper position in a longitudinal direction with respect to the hollow shaft. This construction has necessitated taking apart not only the condenser drum but also the refrigerator drum, in case it was desired 10 to remove the compressor member from the condenser drum. In accordance with this feature of my invention, one can take apart either the condenser or the refrigerator to examine the mechanism, without interfering 15 with the drum which has not been taken apart, and without losing any of the lubricating oil which will settle in one or the other of the drums, depending upon the way in which the machine is set up. To this end 20 my invention consists in providing locking members between the tube and separator so arranged that they hold the tube and the separator against relative rotation, but leave them free to move longitudinally with respect to one another. I preferably also provide means for holding the oil separator in 25 its proper position in a longitudinal direction with respect to the hollow shaft.

For a better understanding of my invention, reference may be had to the following 30 description taken in connection with the accompanying drawing, in which—

Figure 1 is a sectional view of a refrigerating machine embodying my invention; 35 Fig. 2 is a view of a part of the machine of Fig. 1; Fig. 3 is a view of a detail; Fig. 4 is a sectional view taken on the line 4—4 of Fig. 1 and looking in the direction of the arrows; and Fig. 5 is a sectional view taken 40 on the line 5—5 of Fig. 2 looking in the direction of the arrows.

Referring to the drawing, 6 is a hollow shaft which carries and actuates a closed condenser 7 and a closed refrigerator 8, and 45 puts these two members in communication for circulating the gases and liquids. A compressor member 9 is freely suspended from this shaft within the condenser and is weighted by a weight 10 which prevents it 50 from turning with the shaft 6.

In order to keep the lubricant and the refrigerating liquid from mixing and forming an emulsion, I provide one or both of the drums, at their points of greatest diameter, with inwardly extending blades 11 and 12. These blades also preferably extend substantially in the direction of the axis of rotation of the drums, and may be punched out of sheet metal strips 13 and 14. 55 The strip 13 is held in place by centrifugal force between shoulders 15 in the drum 7. The strip 14, which may be formed of two parts, as shown, is held in place by centrifugal force and by crimping the edges thereof 60 of which engage the curved parts of the

drum 8. The ends of the strips may be joined so as to make a complete ring in any suitable way, as by passing one end between two slides on the other end, as shown in Fig. 3 of the drawing. The blades may be 70 of the shape shown in either the condenser drum or the refrigerator drum of Fig. 1.

A tube 16, fastened to the compressor member, extends into the refrigerator.

An oil separator 17 is freely mounted on 75 the shaft 6 within the refrigerator.

In order to hold the oil separator against rotation with reference to the tube and compressor member, I provide locking members 18 and 19 between the tube 16 and the oil 80 separator.

The locking member 18 which is fastened to the tube 16 is preferably a key of peculiar shape which slidably fits into a hole of the same shape in the locking member on the oil 85 separator. This arrangement allows the tube to move longitudinally with respect to the oil separator.

In order to hold the oil separator in its proper position in a longitudinal direction 90 with respect to the hollow shaft but independently of the tube 16, I provide a finger 20 fastened to the separator which fits into a groove 21 in the hollow shaft. If the compressor member has been removed, thereby 95 withdrawing the tube from the refrigerator, it may be readily replaced, the key 18 passing into the hole in the locking member 19 on the oil separator, the oil separator being held from longitudinal movement by 100 the finger 20, and in approximately the correct working position by a counterweight 22.

The compressor member 9 carries compressors and also the mechanism for distributing the lubricating oil and for collecting 105 the same and separating it and for circulating the liquids. The compressors, only one of which is shown in the drawing, are oscillating and double-acting. Each compressor is mounted in the compressor member by means of trunnions 23 and is provided with a piston 24. The piston rods 25 end in collars 26 which embrace the eccentric 27 mounted on the shaft 6, so that the rotation of the shaft reciprocates the pistons. 110 Each oscillating compressor cylinder carries on the inlet side a valve plate 28 furnished with two ports 29 which the oscillations of the cylinder alternately puts in communication with the inlet passages 30 in the compressor member. All the inlet passages open out opposite the end of the hollow shaft. The cylinders of the compressors are held tightly against the valve plates 28 and the compressor member by means of springs 31. 115 The outlet valves of the compressors are not shown in the drawing and may be of any usual construction.

In the construction shown, the chamber 32, which communicates with the outlet 130

valves, has holes 33 in the bottom thereof, (one of which is shown in dotted lines) for allowing the refrigerating liquid, which has been separated from the oil by gravity, to escape into the drum 7. The oil which remains in this chamber is supplied to the working parts of the compressor and to the bearings 34. The liquid in the drum 7 is collected by the scraper 35 and enters the reservoir 36. The refrigerating liquid, which is heavier than the oil which may have escaped with the refrigerating liquid from the chamber 32, settles in the sump 37 from which it is conveyed by a pipe 38 into the chamber 39. The tube 16, which extends into the refrigerator, through the oil separator 17 as explained above, serves to supply the refrigerating liquid to the refrigerator. It is rigidly connected to the compressor member, and consequently does not revolve with the hollow shaft 6 which surrounds it. In the chamber 39 is a valve 40 with a float for controlling the opening of the tube 16 so as to allow liquid to pass into the refrigerator when enough has entered to raise the float. The shaft 6 is also provided with an equalizing valve 41, the object of which is to instantly equalize the pressures as soon as the machine stops, and consequently very rapidly equalize the temperatures in the condenser and refrigerator, by automatically putting them in communication as soon as the machine stops. This valve is closed by a weight 42, thrown out by centrifugal force, and is opened by a spring 43. This weight and the spring 43 are so proportioned that the valve 41 is closed when the machine arrives at 60% of its speed, the valve remaining closed until the machine falls to about 40% of its speed. Without this equalizing valve the refrigerating machine would require a very large motor to start it, much larger than necessary to run it after it has started.

The oil separator 17 comprises a box containing three settling chambers 44, 45, and 46, the chambers 45 and 46 being in effect a single chamber, as they are connected by a pipe 47. This box is supported as explained above and communicates with the interior of the hollow shaft 6. Scrapers 48 and 49 serve to automatically collect and bring into the settling chambers of the separator the refrigerating liquid and oil, the refrigerating liquid being separated from the oil and distributed in a uniform film in contact with the drum 8 and the oil forming a film inside of the refrigerating liquid, by means of the blades 12. The oil and sulfur dioxid separate in these chambers by gravity, the sulfur dioxid settling at the bottom and forcing the oil ahead of it. The excess of sulfur dioxid runs out of tubes 50 and 51 into the drum 8.

The operation of the machine is as fol-

lows: The compressors draw from the refrigerator 8 the gas of the refrigerating liquid, through the hollow shaft 6, into the pockets 52, through cored passages in the compressor member 9 (not shown), inlet passages 30 and 70 ports 29, and after compressing the gas, forces it out through outlet valves (not shown) into the chamber 32 of the compressor member, from which it enters the drum 7 through the holes 33. This gas is thus 75 compressed and liquefied by the compressors. The refrigerating liquid, which under the centrifugal action of the rotating apparatus and by means of the blades 13 is separated from the oil and distributed in a uniform 80 film against the inner side of the condenser drum 7, is continuously collected by the scraper 35 which passes it into the reservoir 36 where it is separated by gravity from any oil which may also be collected by the 85 scraper, the refrigerating liquid entering the chamber 39 through the pipe 38. The refrigerating liquid enters the refrigerator from the chamber 39 through the pipe 16 whenever the valve 40 is open. The evaporation of the refrigerating liquid in the refrigerator cools the drum, and the gas is then pumped back through the hollow shaft 6 as explained above.

A fusible plug 53 seals the end of the refrigerator, and is arranged to blow out at 100° C., as at that temperature the pressure in the drums rises to several hundred pounds per square inch.

I desire it to be understood that my invention is not limited to the particular arrangements shown and described, and I aim in the appended claims to cover all modifications which do not depart from the spirit and scope of my invention.

What I claim as new and desire to secure by Letters Patent of the United States, is:—

1. A rotary refrigerating machine comprising a closed condenser drum, a closed refrigerator drum, a hollow shaft common to both, and means for carrying the liquid contained in one of said drums around with said drum in a substantially uniform film.

2. A rotary refrigerating machine comprising a closed condenser drum, a closed refrigerator drum, a hollow shaft common to both, and means for substantially uniformly distributing the liquid contained in one of said drums about the inner surface thereof at its point of greatest diameter.

3. A rotary refrigerating machine comprising a closed condenser drum; a closed refrigerator drum, a hollow shaft common to both, and blades extending inwardly from one of said drums at its point of greatest 125 diameter and rotating therewith.

4. A rotary refrigerating machine comprising a closed condenser drum, a closed refrigerator drum, a hollow shaft common to both, and a member having inwardly ex-

tending blades mounted at the point of greatest diameter in one of said drums, so as to rotate therewith.

5. A rotary refrigerating machine comprising a closed condenser drum, a closed refrigerator drum, a hollow shaft common to both, and a member having blades mounted at the point of greatest diameter in one of said drums so as to rotate therewith, said 10 blades extending inwardly and substantially in the direction of the axis of rotation.

6. A rotary refrigerating machine comprising a closed condenser drum, a closed refrigerator drum, a hollow shaft common to both, and blades extending inwardly from 15 said drums at their points of greatest diameter and rotating therewith.

7. A rotary refrigerating machine comprising a closed condenser drum, a closed refrigerator drum, a hollow shaft common to both, and members having inwardly extending blades mounted at the points of greatest diameter in both of said drums so as to rotate therewith.

25 8. A rotary refrigerating machine comprising a closed condenser drum, a closed refrigerator drum, a hollow shaft common to both, and members having blades mounted at the points of greatest diameter in both of 30 said drums so as to rotate therewith, said blades extending inwardly and substantially in the direction of the axis of rotation.

9. A rotary refrigerating machine comprising a closed condenser drum, a closed refrigerator drum, a hollow shaft common to both, and a sheet metal member having inwardly extending blades mounted in said condenser drum so as to rotate therewith, and a second sheet metal member having inwardly extending blades mounted in said 40 refrigerator drum so as to rotate therewith.

10. A rotary refrigerating machine comprising a closed condenser, a closed refrigerator, a hollow shaft common to both, a 45 compressor member free on the shaft within the condenser, an oil separator freely mounted on said hollow shaft within the refrigerator, a tube fastened to said compressor member and extending into said refrigerator through said hollow shaft, and locking members between said tube and said separator for holding said tube and said separator against relative rotation but so that they are free to move longitudinally with 50 respect to one another.

11. A rotary refrigerating machine comprising a closed condenser, a closed refrigerator, a hollow shaft common to both, a compressor member free on the shaft within the 55 condenser, an oil separator freely mounted on said hollow shaft within the refrigerator, a tube fastened to said compressor member and extending into said refrigerator through said hollow shaft, locking members between 60 said tube and said separator for holding

said tube and said separator against relative rotation but so that they are free to move longitudinally with respect to one another, and means for holding said oil separator in a longitudinal direction with 70 respect to said hollow shaft but independently of said tube.

12. A rotary refrigerating machine comprising a closed condenser, a closed refrigerator, a hollow shaft common to both, a compressor member free on the shaft within the condenser, an oil separator freely mounted on said hollow shaft within the refrigerator, a tube fastened to said compressor member and extending into said refrigerator through said hollow shaft, and locking members between said tube and said oil separator comprising a key fastened to said tube and a member on said separator having an opening of the same shape as said key for holding said tube and said separator against relative rotation but so that they are free to move longitudinally with 80 respect to one another.

13. A rotary refrigerating machine comprising a closed condenser, a closed refrigerator, a hollow shaft common to both, a compressor member free on the shaft within the condenser, an oil separator freely mounted on said hollow shaft within the refrigerator, a tube fastened to said compressor member and extending into said refrigerator through said hollow shaft, locking members between said tube and said oil separator comprising a key fastened to said tube and a member on said separator having an opening of the same shape as said key for holding said tube and said separator against relative rotation but so that they are free to move longitudinally with 90 respect to one another, and means for holding said oil separator in a longitudinal direction with respect to said hollow shaft but independently of said tube.

14. A rotary refrigerating machine comprising a closed condenser, a closed refrigerator, a hollow shaft common to both, a compressor member free on the shaft within the condenser, an oil separator freely mounted on said hollow shaft within the refrigerator, a tube fastened to said compressor member and extending into said refrigerator through said hollow shaft, locking members between said tube and said oil separator comprising a key fastened to said tube and a member on said separator having an opening of the same shape as said key for holding said tube and said separator against relative rotation but so that they are free to move longitudinally with 100 respect to one another, and means for holding said oil separator in a longitudinal direction with respect to said hollow shaft but independently of said tube.

15. A rotary refrigerating machine comprising a closed condenser, a closed refrigerator,

ator, a hollow shaft common to both, a compressor member free on the shaft within the condenser, an oil separator freely mounted on said hollow shaft within the refrigerator, 5 a tube fastened to said compressor member and extending into said refrigerator through said hollow shaft, locking members between said tube and said separator for holding said tube and said separator against relative 10 rotation but so that they are free to move

longitudinally with respect to one another, said hollow shaft having a groove, and a finger fastened to said oil separator and fitting in said shaft.

In witness whereof, I have hereunto set my hand this 20th day of April, 1914.

JAMES J. WOOD.
